W. LOGG

KEYHOLE LOCK

Filed Aug. 25, 1924

Wendell Logg,

January 1960

R.S. Berry.

Attorney

Patented Sept. 22, 1925.

UNITED STATES PATENT OFFICE.

WENDELL LOGG, OF LOS ANGELES, CALIFORNIA, ASSIGNOR OF ONE-THIRD TO EDWARD BAILEY AND ONE-THIRD TO WILLIAM BATES CATHER, BOTH OF LOS ANGELES, CALIFORNIA.

KEYHOLE LOCK.

Application filed August 25, 1924. Serial No. 733,910.

To all whom it may concern:

Be it known that I, WENDELL LOGG, a subject of King George Fifth of Great Britain and Ireland, residing at Los Angeles, in the county of Los Angeles and State of California, have invented new and useful Improvements in Keyhole Locks, of which the following is a specification.

My invention relates to keyhole locks of the type adapted to be inserted in the lock keyhole in a door that has been locked, to form a secondary lock for said door by preventing the insertion of a key or other lock actuating means in the door keyhole. Secondary locks of the above mentioned type heretofore constructed require to be locked in place by means of a key after being inserted in the door keyhole, and are frequently troublesome to insert and lock and necessitate a considerable waste of time.

The principal object of my invention is to provide a keyhole lock that will automatically lock itself in position on being inserted in the door keyhole.

A further object of my invention is to provide a neat sturdy keyhole lock of the above mentioned type, of few parts and simple construction that can be readily carried on the person.

My invention is illustrated in the accompanying drawings in which:—

Figure 1 is a vertical cross sectional view of a door lock mounted in a door showing my invention in elevation and in operative position in the door keyhole, the door and door lock being broken away.

Figure 2 is a longitudinal vertical sectional view of my complete device showing the action of the automatic locking tongue in dotted lines.

Figure 3 is a sectional view showing my improved keyhole lock unlocked and ready for withdrawal from the keyhole of a door. Figure 4 is a cross sectional view on line 4—4 of Figure 1.

Figure 5 is a cross sectional view on line 5—5 of Figure 2; and

Figure 6 is a cross sectional view on line 6—6 of Figure 3.

Figure 7 is a top plan view of my improved keyhole lock.

Referring now more particularly to Figure 1 a wooden door 7 shown broken away is provided with a vertical slot 8 in the

edge thereof to permit a door lock 9 to be mounted therein. The door lock casing walls 10 and 11 frictionally engage the opposing sides 12 and 13 of the slot 8 and may be held in place therein by screws or other suitable means not shown. Each of said lock casing walls is cut away at 14 and 15, respectively to form the keyholes which keyholes are in alignment with larger though similar shaped keyholes 16 and 17 formed in opposing sides of the wooden door 7 to permit the insertion of the key in the lock.

Referring now more particularly to Figures 2 and 5 which show my invention embodied on a keyhole lock of the well known "Yale" construction. A stem 18 provided with a free hollow end portion 19 is rotatably mounted in a lock cylinder 20 formed integral with a tumbler casing 21 depending therefrom and is prevented from endwise movement therein by means of an annular flange 22 formed integral with the outer end of said stem engaging in an annular bearing 23 formed in the outer end of said cylinder, and a ring member 24 sweated to the outside of the stem intermediate its length and engaging the inner end 25 of said lock cylinder.

Spring actuated lock tumblers 26 slidable in parallel slots 27 formed in the tumbler casing 21 normally engage co-acting tumblers 28 of varying lengths and slidably in corresponding parallel slots 29 in the stem 18 to prevent rotation thereof and may be brought out of engagement therewith by means of a specially constructed key 30 inserted in a longitudinal slot 31 formed in the stem 18 and opening into the tumbler slots 29; said key is provided with notches 32 of varying sizes which notches engage the predetermined co-acting tumblers 28 when the key is inserted in the lock so as to bring the tumblers 26 clear of the stem, whereupon the stem may be rotated.

So as to make the keyhole lock automatically lock itself in position when inserted in a door keyhole, I form the free end 19 of the stem hollow and secure therein a plate 33 by means of a pivot 34 passed through a hole in the neck 35 thereof and secured at its ends to opposing sides of said hollow stem. Said hollow stem portion is provided with an upper and a lower slot 36 and 37, respectively, to permit the ver-

tical play of said plate member 33; the upper slot 36 is formed smaller than the lower slot 37 so as to form a shoulder 38 to limit the upward movement of said plate by engaging the edge 39 thereof. A wedge shaped locking tongue 40 is formed integral with the upper edge of said plate and protrudes through the slot 36 when in normal position. A spiral spring 42 secured between two plug members 43 and 44 within the hollow end of the stem resiliently holds the plug 44 against the point 45 of the neck 35 of the plate 33 thereby causing the edge 39 of the plate to engage the shoulder 38 and hold the tongue in locking position.

The plug 44 is preferably made as a ball as shown in Figure 2.

Referring now to the operation of my device. When the stem 18 is inserted in the keyhole 17 of the door 7 the edge 46 of the tongue resiliently engages the upper edge 47 of the keyhole 15 in the lock casing wall 11 which depresses the tongue 40 as the stem is advanced in the keyhole (see dotted lines in Figure 2) until the tongue passes the door lock casing wall 11 whereupon it snaps back into locking position because of the removal of the resistance offered by the upper edge of the door lock keyhole and the action of the spiral spring 42 on the neck 35 of the plate 33. To prevent the keyhole lock from being passed completely through the keyhole the ring member 24 is formed large enough to engage the face of the lock casing wall 11, around the keyhole 15.

To prevent rotation of the keyhole lock when in locked position the tumbler casing 21 is formed with a lug 48 forming an extension thereof and disposed on the lower side of the stem and in the same plane as the locking plate 33, said lug is adapted to lodge in the door keyhole when the keyhole lock is in operating position thereby

preventing rotation of the keyhole lock. To remove my improved keyhole lock from the keyhole of a door it is necessary to insert the key 30 in the longitudinal slot 31 so as to actuate the Yale tumbler lock and rotate the stem one-half turn whereupon the tongue is brought in line with the lower part of the door keyhole and the lock may be readily withdrawn. (See Figure 3).

Obviously many changes may be made in my device without departing from the spirit of my invention and I claim as within the scope of my invention all forms readable on the claims that will be finally allowed on this application.

I claim:

1. In a keyhole lock the combination of a lock cylinder, a stem rotatable in said cylinder, means for controlling the rotation of said stem in said cylinder, said stem provided with a free hollow end portion, a locking plate pivoted within said hollow end portion and adapted to protrude through a slot formed in said stem when in locked position and means for resiliently holding said plate in locked position.

2. In a keyhole lock the combination of a lock cylinder, a stem rotatable in said cylinder, means for controlling the rotation of said stem in said cylinder, said stem provided with a free hollow end portion, a locking plate pivoted within said hollow end portion and adapted to protrude through a slot formed in said stem when in locked position, a spiral spring disposed between two plugs within said hollow end portion and adapted to resiliently hold one of said plugs in contact with the neck of said locking plate to resiliently hold said locking plate in locked position and means for preventing the rotation of said cylinder in a door keyhole.

WENDELL LOGG.
